(57) **CLAIM**

We claim the ornamental design for a cradle for mobile terminals, as shown and described.

DESCRIPTION

FIG. 1 is a perspective end view of a cradle for mobile terminals according to the present invention.

FIG. 2 is a second perspective end view of the cradle for mobile terminals of FIG. 1.

FIG. 3 is a top view of the cradle for mobile terminals of FIG. 1.

FIG. 4 is a left side view of the cradle for mobile terminals of FIG. 1.

FIG. 5 is a right side view of the cradle for mobile terminals of FIG. 1.

FIG. 6 is a first end view of the cradle for mobile terminals of FIG. 1; and,

FIG. 7 is a second end view of the cradle for mobile terminals of FIG. 1.

The bottom of the cradle for mobile terminals of FIG. 1 is flat and devoid of surface ornamentation.

The portions shown in broken line are not claimed.

The appearance of any portions of the cradle which are not shown in the drawings is not claimed.

Broken lines and unshaded portions contained within broken lines are not claimed.

1 Claim, 7 Drawing Sheets
